DESIGN FOR A TILLER

Cadwallader W. Kelsey, Troy, N. Y.

Application April 14, 1939, Serial No. 84,275

Term of patent 14 years

To all whom it may concern:

Be it known that I, Cadwallader W. Kelsey, a citizen of the United States, residing in the city of Troy, county of Rensselaer, and State of New York, have invented a new, original, and ornamental Design for a Tiller, of which the following is a specification, reference being had to the accompanying drawing, forming part thereof.

Fig. 1 is a top view of a tiller embodying my design;

Fig. 2 is a side elevation thereof; and

Fig. 3 is a front view of the tiller shown in the preceding views.

I claim:

The ornamental design for a tiller, as shown.

CADWALLADER W. KELSEY.
